UNITED STATES PATENT OFFICE

2,439,599

LIFTING MECHANISM FOR INDUSTRIAL TRUCKS

Herbert J. Framhein, Chicago, Ill., assignor to
The Yale & Towne Manufacturing Company,
Stamford, Conn., a corporation of Connecticut

Application April 6, 1943, Serial No. 481,957

12 Claims. (Cl. 254—2)

1

This invention relates to a truck of the type having a lifting head and an elevating platform, the elevating platform being adapted for lifting movement relatively to the lifting head. More particularly, this invention relates to that type of truck disclosed in my application Serial No. 432,177, filed February 25, 1942, now Patent No. 2,399,596, dated April 30, 1946.

In my earlier application supra, the elevating platform is shown mounted at its forward end for lifting movement relatively to a lifting head, lifting wheels being mounted at the rear end of the elevating platform for lifting the rear end of the platform as the forward end is lifted. In my earlier application the rear lifting wheels of the elevating platform are adapted to be moved through cams mounted on the lifting head and actuated incidental to the lifting of the forward end of the elevating platform as that forward end moves upwardly relatively to the lifting head.

I have conceived it highly desirable that the lifting cams be mounted on the elevating platform provided this can be done advantageously and in such a manner that the said cams may be readily actuated as the forward end of the elevating platform is moved upwardly relatively to the lifting head. To obtain such means is extremely difficult in a truck of the class having a lifting head and an elevating platform, and the conception of such means and their reduction to practice has been a considerable problem.

A feature of this invention resides in the means whereby the lifting cams are mounted on the elevating platform for actuation by means on the lifting head as the cams move upwardly with the elevating platform. A further feature resides in the arrangement of the parts whereby they do not interfere with the under clearance of the truck.

More particularly, it is a feature of my invention that the lifting cams are adapted for mounting on an elevating platform that is moved vertically relatively to a lifting head, and with the said elevating platform being assembled on the lifting head and maintained against pivotal movement relatively thereto at all times. As a more detailed feature of the invention the elevating platform on which the cams are mounted is adapted for vertical movement through rollers and channels that serve to mount the elevating platform for vertical sliding movement while maintaining the platform against pivotal movement on the lifting head.

Actually, it is the conception of suitable means for the mounting of the lifting cams for pivotal movement relatively to the elevating platform

2

and in a position to be moved pivotally relatively to the platform by means on the lifting head, that forms the main basis of the invention of this application.

I have thus described generally my invention in order that its relation to the prior art and the contribution thereof to the prior art may be better appreciated. For a description of the invention and of a preferred mechanical form thereof, I shall refer to the accompanying drawings and the description that follows. Those skilled in the art will of course appreciate that once the basis of my contribution to the art is disclosed to those skilled in the art, it will be possible for those skilled in the art to develop mechanisms different from that I shall herein describe but yet effective to contribute the operations and results contributed by my invention. It is important therefore that my patent claims should not be limited to the specific disclosure I shall herein show and describe.

Referring now to the drawings

Fig. 1 is an elevation and partial section of a truck embodying my invention.

25 Fig. 2 is a view looking downwardly on the rear end of the truck of Fig. 1.

Fig. 3 is an enlarged elevation and partial section of part of Fig. 1.

30 Fig. 4 is a section taken vertically just outside the plane of the vertical ram of my truck and showing the parts of Fig. 3 when the elevating platform is lifted relatively to the lifting head.

Fig. 5 is an exploded view showing the rear end of the lifting head and the forward end of the elevating platform.

Referring now more particularly to the drawings, and especially Figs. 1 and 5, the lifting head of my truck is designated generally by reference numeral 10. The forward end of this lifting head is supported by driving wheels 11 forming part of a steering head 12 on which is mounted a traction unit 13 adapted to drive the wheels 11. A controlling and steering lever for the steering head of the truck is designated by reference numeral 14 and is pivoted at 15 to the steering head 12. This construction is fully illustrated and described in my patent application Ser. No. 390,931, filed April 29, 1941, now Patent No. 2,327,583, dated August 24, 1943, for a 45 Motorized lift truck, and need not be described in any more detail here. It is obvious of course that my invention need not necessarily be used in a motorized truck, such a truck being shown here merely as illustrative of one form of truck. 50 The rear end of the lifting head, as shown best

in Fig. 5, has a pair of vertical uprights 16 formed with channels 17. The upper ends of the uprights 16 are braced by a crossbar 18 that is assembled to the uprights through the intermediary of angle bars 19. At this point it may be well to indicate that the present practice in the lift truck art is to fabricate parts as illustrated by me in the drawings, but those skilled in the art will appreciate that the parts may be fabricated in other ways as manufacturing processes change and develop.

For imparting lifting movement to the elevating platform to be described presently, my lifting head carries a hydraulic lifting ram assembly 20. This hydraulic assembly, as is best seen in Figs. 4 and 5 is equipped with a lower ear 21 mounted on a pin 22, the pin 22 being carried in suitable bores 23 of bearing blocks 24 that are welded or otherwise secured to a plate 25. The plate 25 is secured to the lower ends of the uprights 16 and to side plates 26 of the lifting head 10 to form an integral part of the lifting head.

The hydraulic ram assembly 20 carries a ram plunger 27, the upper end of which is formed with an ear 28 whereby through a stub shaft 29 it may be pivotally secured to a pair of brackets 30, best shown in Fig. 5 as welded or otherwise secured to the vertical standard 31 of the elevating platform 32. It is obvious, of course, that vertical movement of the ram plunger 27 will effect the upward movement of the vertical standard 31 of the elevating platform 32.

The elevating platform 32 has mounted on its vertical standard 31 a pair of vertical plates 33. Each of these vertical plates carries a pair of rollers 34 in the standard manner known in the art. These rollers 34 are formed to fit within the channels 17 of the vertical uprights 16 of the lifting head so as to guide the elevating platform 32 for vertical movement relatively to the uprights 16. It is obvious also, that the rollers 34 lying in the channels 17 as shown best in Fig. 2, maintain the elevating platform assembled to the lifting head and against pivotal movement relatively thereto.

The elevating platform 32 is formed in the shape of a U in common with a known practice in the industrial lift truck art. The legs of this U are of course alike except that they are in opposite relation as is well illustrated in Fig. 2. I shall now describe the construction of one leg of the U platform and the means whereby lifting means carried thereby is actuated by devices mounted on one side of the lifting head.

Referring to Figs. 1, 2 and 5, the leg 40 of the elevating platform 32 is shown as having an upper plate 41 formed with an opening at 42 to expose a rear wheel lifting link 43. The link 43 is pivoted through the shaft 44 to bearing lugs 45 forming a part of the leg 40. Lugs 46 on the link bear against surfaces 47 on the leg 40 to limit rotation in one direction of the link 43 relatively to the leg. A lifting wheel 48 is mounted on an axle 49 carried by the link 43 so as to rotate on the said axle, and so as to move with the link to lift the rear end of the elevating platform. For so moving the lifting link 43, I rely on a rod assembly 50 that is pivoted at its rear end to the lifting link 43 about a pin 51. It is obvious now that movement to the left of the rod assembly 50 in Figs. 1 and 2 will effect lifting movement of the rear wheel lifting link 43. The construction of the U leg and the parts just described is old in the art and per se is not my invention. My invention includes means for moving the rod as-

semblies 50 of the U legs 40 to effect the lifting movement of the rear wheel lifting links 43, as will of course be apparent to those skilled in the art.

At its forward end, each rod assembly 50 is pivoted through a stub shaft 53 to a lifting cam 54. I shall describe but one of these cams and its actuating means. The lifting cam 54, as best seen in Fig. 5, is pivoted about a shaft 55 that extends between a pair of parallel brackets 56, the shaft 55 being suitably carried by the brackets. The brackets 56 are secured as by welding or by bolting, as the case may be, to the vertical standard 31 of the elevating platform 32. In the preferred form of my invention the pair of brackets 56 are integral parts of a U shape bracket assembly having a rear plate 57 as is quite apparent from Fig. 5. Because of this mounting of the cam 54, it is movable bodily with the elevating platform while rotatable on its pivot relatively thereto.

The cam 54 is formed with a cam surface 58 adapted to cooperate with a roller 59 extending outwardly from the plate 26 of the lifting head. The roller 59 may be mounted on the plate 26 in any preferred manner and extends through a slot 60 in the bracket 56 adjacent thereto so as to occupy a position overlying cam 54 and with its periphery against the cam surface 58 of the cam 54. There are of course two rollers 59, one at each side of the lifting head.

Referring now to Fig. 3, we find the parts there in the position in which they lie when the elevating platform 32 of the truck is in its fully lowered position. It will be noted therefore that the particular roller 59 shown is near the upper end of the slot 60 of the particular bracket 56 illustrated. We note also that the right hand end of the cam surface 58 is under the roller 59 in a position to rotate the cam 54. The lifting wheels 48 at the rear end of the platform are of course in the lowered position illustrated in Fig. 1, the cam 54 in that figure lying in the same position as in Fig. 3.

If now the hydraulic lifting ram assembly 20 is actuated, the ram plunger 27 will move vertically and will through the shaft 29 move the elevating platform 32 and its standard 31 into the position of Fig. 4. The position of Fig. 4 is the elevated position of the elevating platform as will be apparent. During this upward movement of the elevating platform the roller 59 has been held against vertical movement and therefore occupies now a position near the lower end of the slot 60 in the particular bracket 56 that is illustrated. The cam 54, having moved upwardly from the position of Fig. 3 to the position of Fig. 4 through its pivotal mounting on shaft 55 of the brackets 56, has been rotated by the roller 59, this rotation taking place about the shaft 55. During this rotary movement, the cam 54 of course, through the pin 53 imparted a considerable movement to the left to the rod assembly 50. This movement of the rod assembly 50 has effected the lifting movement of the particular lifting link 43 and wheel 48 actuated by the particular rod assembly 50 illustrated.

Therefore while the elevating platform 32 was being lifted at its forward end, the rear end of the platform was also being lifted through the intermediary of the pair of cams 54, the rod assemblies 50, and the lifting wheels 48.

I believe that the operation and construction of my invention will now be quite apparent to those skilled in the art.

I now claim:

1. In a truck of the class described, a lifting head having a vertical standard, an elevating platform having a forward vertical standard, rollers on said platform standard moving in channels on said lifting head standard, lifting wheels at the rear end of said elevating platform, means mounting said lifting wheels for lifting movement relatively to said elevating platform, lifting means for lifting the forward standard of said elevating platform relatively to said lifting head, lifting cams pivoted on said elevating platform, means of connection between said lifting cams and said lifting wheel mounting means whereby pivotal movement of said lifting cams effects movement of said lifting wheels in a lifting direction, and means fixed on said lifting head and bearing against said lifting cams to pivot said lifting cams as said cams move with said elevating platform relatively to said lifting head.

2. In a truck of the class described, a lifting head, an elevating platform, means mounting said platform for vertical movement relatively to said lifting head and holding said platform against pivotal movement relatively to said lifting head, lifting wheels at the rear end of said elevating platform, means mounting said lifting wheels for lifting movement relatively to said elevating platform, lifting means for lifting the forward end of said elevating platform relatively to said lifting head, lifting cams pivoted on said elevating platform, means of connection between said lifting cams and said lifting wheel mounting means whereby pivotal movement of said lifting cams effects movement of said wheels in a lifting direction, and means fixed on said lifting head and bearing against said lifting cams to pivot said lifting cams as said cams move with said elevating platform relatively to said lifting head.

3. In a truck of the class described, a lifting head having a vertical standard, an elevating platform having a forward vertical standard, rollers on said platform standard moving in channels on said lifting head standard, lifting wheels at the rear end of said elevating platform, means mounting said lifting wheels for lifting movement relatively to said elevating platform, lifting means for lifting the forward standard of said elevating platform relatively to said lifting head, lifting cams pivoted on said elevating platform and movable bodily with said elevating platform, means of connection between said lifting cams and said lifting wheel mounting means whereby pivotal movement of said lifting cams effects movement of said lifting wheels in a lifting direction, and rollers mounted on shafts fixed to said lifting head and bearing against said lifting cams to pivot said lifting cams as said cams move with said elevating platform relatively to said lifting head.

4. In a truck of the class described, a lifting head having a vertical standard, an elevating platform having a forward vertical standard, means mounting said platform standard for vertical movement relatively to said lifting head standard while maintaining said standards in spaced relation, lifting wheels at the rear end of said elevating platform, means mounting said lifting wheels for lifting movement relatively to said elevating platform, lifting means for lifting the forward standard of said elevating platform relatively to said lifting head, lifting cams pivoted on said elevating platform, means of connection between said lifting cams and said lifting wheel mounting means whereby pivotal movement of said lifting cams effects movement of said lifting wheels in a lifting direction, and a roller mounted on a stub shaft at each side of said lifting head and extending through an opening in a bracket of each of said pair of brackets so as to overlie the cams pivoted between said brackets, said rollers acting to pivot said lifting cams on their shafts as said

ment of said lifting cams effects movement of said wheels in a lifting direction, and rollers mounted on shafts fixed to said lifting head and bearing against said lifting cams to pivot said lifting cams as said cams move with said elevating platform relatively to said lifting head.

5. In a truck of the class described, a lifting head having a vertical standard, an elevating platform having a forward vertical standard, rollers on said platform standard moving in channels on said lifting head standard, lifting wheels at the rear end of said elevating platform, means mounting said lifting wheels for lifting movement relatively to said elevating platform, lifting means for lifting the forward end of said elevating platform relatively to said lifting head, a pair of brackets projecting from said elevating platform at each side thereof, a lifting cam pivoted between the brackets of each of said pair of brackets on a shaft extending between said brackets, means of connection between said lifting cams and said lifting wheel mounting means whereby pivotal movement of said lifting cams effects movement of said lifting wheels in a lifting direction, and rollers mounted on shafts fixed to said lifting head and bearing against said lifting cams to pivot said lifting cams as said cams move with said elevating platform relatively to said lifting head.

6. In a truck of the class described, a lifting head, an elevating platform, means mounting said platform for lifting movement relatively to said lifting head, lifting wheels at the rear end of said elevating platform, means mounting said lifting wheels for lifting movement relatively to said elevating platform, lifting means for lifting the forward end of said elevating platform relatively to said lifting head, a pair of brackets projecting from said elevating platform at each side thereof, a lifting cam pivoted between each of said pair of brackets on a shaft extending between said brackets, means of connection between said lifting cams and said lifting wheel mounting means whereby pivotal movement of said lifting cams effects movement of said wheels in a lifting direction, and rollers mounted on shafts fixed to said lifting head and bearing against said lifting cams to pivot said lifting cams as said cams move with said elevating platform relatively to said lifting head.

7. In a truck of the class described, a lifting head having a vertical standard, an elevating platform having a forward vertical standard, rollers on said platform standard moving in channels on said lifting head standard, lifting wheels at the rear end of said elevating platform, means mounting said lifting wheels for lifting movement relatively to said elevating platform, lifting means for lifting the forward end of said elevating platform relatively to said lifting head, a pair of brackets projecting from said elevating platform at each side thereof, a lifting cam pivoted between the brackets of each of said pair of brackets on a shaft extending between said brackets, means of connection between said lifting cams and said lifting wheel mounting means whereby pivotal movement of said lifting cams effects movement of said lifting wheels in a lifting direction, and a roller mounted on a stub shaft at each side of said lifting head and extending through an opening in a bracket of each of said pair of brackets so as to overlie the cams pivoted between said brackets, said rollers acting to pivot said lifting cams on their shafts as said

cams move with said elevating platform relatively to said lifting head.

8. In a truck of the class described, a lifting head, an elevating platform, means mounting said elevating platform for lifting movement relatively to said lifting head, lifting wheels at the rear end of said elevating platform, means mounting said lifting wheels for lifting movement relatively to said elevating platform, lifting means for lifting the forward end of said elevating platform relatively to said lifting head, a pair of brackets projecting from said elevating platform at each side thereof, a lifting cam pivoted between each of said pair of brackets on a shaft extending between said brackets, means of connection between said lifting cams and said lifting wheel mounting means whereby pivotal movement of said lifting cams effects movement of said wheels in a lifting direction, and a roller mounted on a stub shaft at each side of said lifting head and extending through an opening in a bracket of each of said pair of brackets so as to overlie the cams pivoted between said brackets, said rollers acting to pivot said lifting cams on their shafts as said cams move with said elevating platform relatively to said lifting head.

9. In a truck of the class described, a lifting head having a vertical standard, an elevating platform having a forward vertical standard, rollers on said platform standard moving in channels on said lifting head standard, lifting links pivoted to the rear end of said platform, lifting wheels movable with said links to lift the rear end of the platform, lifting means for lifting the forward standard of said elevating platform relatively to said lifting head, lifting cams pivoted on said elevating platform, rods connecting said cams to said lifting links whereby pivotal movement of said lifting cams effects lifting movement of said lifting links and lifting wheels, and rollers mounted on shafts fixed to said lifting head and bearing against said lifting cams to pivot said lifting cams as said cams move with said elevating platform relatively to said lifting head.

10. In a truck of the class described, a lifting head, an elevating platform mounted for elevating movement relatively to said lifting head, a pair of spaced brackets at each side of the forward end of said elevating platform, a pivot shaft extending between the spaced brackets of each pair of brackets, a cam pivoted on each of said shafts and having a curved lifting surface integral therewith, a rod pivoted to each of said cams and extending toward the rear end of said platform, lifting wheels at the rear end of said elevating platform connected to said rods for movement by said rods, lifting mechanism for lifting

5 said elevating platform relatively to said lifting head, and means fixed to said lifting head extending through openings in certain of said brackets for contact by the lifting surfaces of said cams as said cams move with said elevating platform whereby said cams are rotated on their pivots to actuate said rods and lifting wheels.

11. In a truck of the class described, a lifting head, an elevating platform mounted for elevating movement relatively to said lifting head, a pair of spaced brackets at each side of the forward end of said elevating platform, a pivot shaft extending between the spaced brackets of each pair of brackets, a cam pivoted on each of said shafts, a rod pivoted to each of said cams and extending toward the rear end of said platform, lifting wheels at the rear end of said elevating platform connected to said rods for movement by said rods, lifting mechanism for lifting said elevating platform relatively to said lifting head, and rollers mounted on shafts fixed relatively to said lifting head and contacted by said cams as said cams move with said elevating platform whereby said cams are rotated on their pivots to actuate said rods and lifting wheels.

12. In a truck of the class described, a lifting head, an elevating platform mounted for elevating movement relatively to said lifting head, a pair of spaced brackets at each side of the forward end of said elevating platform, a pivot shaft extending between the spaced brackets of each pair of brackets, a cam pivoted on each of said shafts, a rod pivoted to each of said cams and extending toward the rear end of said platform, lifting wheels at the rear end of said elevating platform connected to said rods for movement by said rods, lifting mechanism for lifting said elevating platform relatively to said lifting head, and rollers mounted on shafts fixed relatively to said lifting head and contacted by said cams as said cams move with said elevating platform whereby said cams are rotated on their pivots to actuate said rods and lifting wheels, said rollers protruding through openings in a bracket of each pair of brackets into a position overlying said cams.
